15 Claims. (Cl. 250—27.5)

The present invention relates to electron discharge tubes and particularly to high power tubes.

The invention particularly relates to improvements in the various elements forming an electron discharge tube and new arrangements of the different elements so as to produce an improved tube having a large number of desirable characteristics.

It is well known that in high power vacuum tubes it is necessary for the spacing of the various electrodes to be relatively small so that the tubes may have the desired electrical characteristics. However, when the electrodes such as the cathode and grid are very near, short circuits are often produced between the filament and the grid which disrupt operation of the device. It has been found that among the frequent causes of such short circuits there are, on the one hand, the unequal expansion of various elements of the tube, for example, the filament expanding more than the grid, and on the other hand, electrodynamic forces develop between the various conductors forming the cathode. These electrodynamic forces in the case of high power tubes are often sufficiently great to separate very considerably the conductors forming the cathode, and even sometimes to cause untimely contacts between the elements of the cathode and other elements of the tube.

An object of the invention is to provide a vacuum tube particularly adapted for high power and for very high frequencies and in which the above disadvantages are eliminated.

Another object of the invention is to provide a vacuum tube of the type mentioned, which may be of exact and simple construction and which can be easily mounted and sealed, for example, by means of a rotary machine.

Another object of the invention is to provide an improved arrangement of the various elements of such a tube permitting of very great precision in the arrangement and fixing of the elements.

In order to explain the nature and the various aspects of the present invention, a number of characteristic features of the invention will be set forth and it should, of course, be understood that one or more of these characteristics may be employed either singly or in combination.

Moreover, a vacuum tube comprising the characteristics of the invention will be described in detail and it should be noted that in the course of the description of this tube a number of equally important characteristics of the invention will be indicated.

According to one of the characteristics of the invention, the various elements of an electron discharge tube are arranged symmetrically, for example, concentrically, with respect to an axis which may be established during the mounting 60 of the tube by means of a special tool, the tool being adapted to be removed when the mounting is complete, which enables the tube to be conveniently mounted, for example, by a special rotary machine.

Another feature of the invention relates to a vacuum tube comprising a cathode supported by two tubular concentric conductors also serving to supply current to the cathode and moreover, a control electrode supported by a tubular conductor serving as electrical connection for the control electrode, the cathode and the control electrode being preferably arranged about the same axis.

According to another feature of the invention, 75 the cathode of a vacuum tube of the type described is supported at one end by two tubular concentric conductors serving to supply the current to the cathode, and at the other end, is supported by means of one or more metallic rods 80 supported by the tubular conductor serving as support and electrical connection for the grid, means being provided to apply a well-defined tensioning force to the metallic rod supporting the cathode.

According to another characteristic of the invention, the two tubular concentric conductors serving as supports and electrical connections for the filaments are fixed on the envelope of the tube in the following manner. The outer conductor is sealed to the vitreous envelope of the tube while the space between the two concentric conductors is closed by means of a piece of glass of suitable shape soldered to the tubular conductors.

Another feature of the invention relates to an electron discharge tube comprising a tubular anode adapted to receive at each of its extremities a glass portion, through one of which the tubular grid-support-conductor passes while 100 through the other portion the two concentric tubular filament-supporting-conductors pass.

According to one feature of the invention, in a vacuum tube of the type described, the filament is held under tension by means of a rod 105 sliding in insulators fixed to the tubular conductor which serves both as grid support and electrical connection for the grid.

Another characteristic consists in the case of a filament comprising several strands, in the provi- 110

sion of means to equalize the effort, for example, of traction, on each of the strands and to prevent the lateral displacement or harmful distortion of the strands. For this purpose, at one 5 of the ends of the filament, the supporting system employed may be mounted on a swivel and small balancing rods may or may not be provided.

Another feature of the invention consists of a 10 vacuum tube comprising a tubular anode at each extremity of which a glass portion may be sealed. The anode may or may not be provided with a jacket for the circulation of a cooling fluid. One of these portions supports two concentric 15 tubular conductors serving as a support for one of the ends of the cathode and electrical connections for the cathode. The other glass portion sealed to the anode is adapted to support a tubular conductor to which the grid is fixed, this 20 tubular conductor serving to convey the current to the grid and also as a support for one or more rods on which the other end of the filament is fixed. Means may be provided and associated with the rod or rods to maintain the filament 25 stretched.

According to another feature of the invention, a jacket for the circulation of a cooling fluid for the tube of the type described comprises a metallic member approximately concentric with the 30 anode, arranged with respect to the anode so as to leave a free space forming a jacket for the circulation of a cooling fluid, the cooling fluid being conveyed into the jacket by means of an inlet placed approximately in the middle of the 35 anode and the removal of the cooling fluid being performed by means of two outlets placed approximately at the two ends of the jacket. Pieces of suitable shape are provided inside the jacket to reduce the section or sections of passage of the 40 cooling fluid in contact with the anode, or on the greater portion of the anode and to force the fluid to circulate at high speed in a thin layer so as to insure a maximum exchange of heat between the anode and the cooling fluid.

45 Other features of the invention will be seen by referring to the following description based on the attached drawing in which:

Fig. 1 shows a cross-sectional view of a high power vacuum tube employing the characteristics 50 of the present invention;

Fig. 2 is a section perpendicular to the axis of the vacuum tube on the line A—B of Fig. 1 showing the tubular conductor which acts as a support for the grid;

55 Fig. 3 is a section perpendicular to the axis of the vacuum tube on the line C—D of Fig. 1 showing the arrangement of the various electrodes and of the circulation jacket for the cooling fluid;

Fig. 4 is a section perpendicular to the axis of 60 the vacuum tube on the line E—F of Fig. 1 showing the arrangement of a reflector;

Fig. 5 is a cross-sectional view on the line G—H of Fig. 1;

Fig. 6 is a partial cross-sectional view on the 65 line I—J of Fig. 1 showing in detail the arrangement of the rods for conveying current and fixing the cathode on the concentric supporting conductors; and

Figs. 7, 8 and 9 are enlarged views of the 70 articulate support for one end of the cathode.

Fig. 1 shows a longitudinal section of an electron discharge tube employing the features of the present invention. In a general manner the tube shown in Fig. 1 is a tube of the double-ended type, 75 that is to say, the anode is formed by a metallic

tube at each end of which a glass portion is sealed. In Fig. 1 the connections of the cathode and the grid are carried out by means of tubular conductors which in the case of the cathode conductors may be formed by means of two tubes, one passing inside the other, for example, concentrically. In Fig. 1 the tubular conductors serve at the same time as supports for the corresponding electrodes. The two concentric conductors are adapted, among other functions, to convey current to the cathode and may, in accordance with the drawing, be placed at one end of the vacuum tube, while the tubular conductor serving, among others, to convey current to the grid, is placed at the opposite end of the vacuum tube, that is to say, the latter tubular conductor is supported by one of the glass portions sealed to the anode. It will be noted that the anode is provided with a jacket for the circulation of cooling fluid of a particular type which will be described herein- 85 after in detail.

In Fig. 1, the tubular anode is shown at 1 and the two glass portions sealed to the ends of the anode 1 are shown at 2 and 2'. The electrical connections to the cathode, illustrated in the form 100 of filaments 3, are established by means of two tubular concentric conductors 4 and 5, sealed to the glass portion 2' by means of a conical metallic member 6 soldered on the outer tubular conductor 4. The tubular conductor 4 terminates in a 105 flare to enable an auxiliary glass portion 2'1 to be sealed thereto, one part of which is soldered to a conical metallic member 7 similar to the member 6 described above. The auxiliary portion 2'1 serves to close the space comprised between the 110 two tubular conductors 4 and 5. Finally, the end of the conductor 5 is closed by means of a suitable stopper, such as a copper disc 8, soldered to the conductor 5. The manner in which the filaments are supported from the ends of the conductors 4 and 5 will be described later in detail. The current is conveyed to the grid by means of 115 a tubular conductor 9, one end of which is flared to permit sealing of a glass portion 21 thereto. The pumping of the vacuum tube may be performed by connecting a vacuum pump to the portion 21 and sealing this portion when the desired 120 degree of vacuum has been obtained. A conical metallic portion 10 is soldered, on the one hand, to the tubular conductor 9 and, on the other hand, 125 sealed to the glass portion 2. At one of the extremities of the tubular conductor 9 there is fixed, by means of the screw 33, an apertured disc 11 supporting the control or grid electrode of the tube. The grid is constructed of a molybdenum 130 wire 34, wound helically, as shown in Fig. 3, on four rods 12 fixed on the disc 11. To prevent the relative position of the turns 34 from varying, suitable means are provided to maintain the turns 135 in position on the rod 12.

It will be noted that the disc 11 must be relatively thick to permit the rigid fixing of the rods 12. This disc being supported with the conductor 9 by the glass portion 2, it is advisable to reduce its weight and for this purpose easing holes may be 140 provided in the disc 11.

The cathode comprises a plurality of filaments 3 which are maintained in position in the following manner: On the one hand, the concentric conductors 4 and 5 support rods 13 to which the filaments 3 are fixed, forming the cathode. These filaments are held in position by means of hooks 14 fixed to a particular member 15 which will be described further on in detail. The member 15 is mounted on a rod 16 supported by suitable 145

means in the tubular conductor 9; serving to convey current to the grid. The rod 16 may be held in position in the conductor 9 by any suitable means; in particular, blocks of insulating material 17 and 18, of which Fig. 2 shows a plan view, may be provided and arranged in the tubular conductor 9 as shown in Fig. 1. In order that the tensioning force exercised on the filaments 3 forming the cathode may be adjusted to a determined value, a spring 19 may be provided and associated with the rod 16. A nut 20 whose position may be adjusted on a threaded portion of the rod 16, serves to control the compression of the spring 19 and consequently the tension applied to the filaments 3 forming the cathode. The spring 19 may be formed of a metallic wire which retains its elasticity at high temperatures, for example, tungsten, so as to maintain the desired tension on the sections of the cathode 3. It will be noted that the tubular conductor 9 is provided with a series of holes 21, adapted to reduce the weight of the member supported by the glass portion 2, as well as the transmission of heat from the grid towards the members sealed to the glass.

The arrangement of the blocks of insulating material 17 and 18 is clearly shown in Fig. 2, which is a section of the tube along the line A—B. The blocks of insulating material 17 and 18 are fixed in position in the tube 9 by means of a sheath 35 of the shape shown in the drawing. This sheath 35 is kept inside the tubular conductor 9 in the position shown in Fig. 1 by the reaction of the spring 19. The blocks 17 and 18 are each provided with a groove 38 in which is set the metal of the sheath 35 which fixes the position of the blocks 17 and 18 in the sheath. The position of the sheath in the conductor 9 is fixed by means of a boss 39 which is applied to the flared portion of the tubular conductor 9. The sheath 35 is provided with an extension 40 serving as an electrostatic screen protecting the metal-glass sealing.

In order that the rod 16 may slide suitably in the insulating blocks 17 and 18, these blocks are each provided with a hole of a slightly larger diameter than that of the rod 16 and a sheath formed of the same metal as the rod 16, for example, a wire spiral with touching strands 36 is provided inside the opening so that the friction is made between two metals of the same nature. To prevent the helical spiral 36 from turning or being displaced, the ends of the wire forming this spiral may engage the holes 37 provided in the member 17, or any other fixing means may be employed. In Fig. 2 it will be noted that the member 17 is provided with openings 41 which serve, in particular, to facilitate the pumping of the tube and to lighten this member.

Special precautions have been taken to prevent short circuits between the filaments and the grid under the influence of the considerable electrodynamic forces developed by the heating current of the filaments. Figs. 7, 8 and 9 represent the arrangement employed for this purpose. This arrangement, moreover, is shown at 14 and 15 in Fig. 1. Referring particularly to Fig. 7, it will be noted that the rod 16, Fig. 1, is screwed into the member 42 to which is fixed, by means of three stays 43, a similar member 45 having a pin 46 with a spherical head 47. The spherical head 47 engages the concave portion of an intermediate member 48 having three axles 49, 49' and 49'', clearly shown in Fig. 8. Each of the axles carries transversely at its extremity a rod, such as 50, at the ends of which are joined two hooks 51 and 52. The rod 50 may oscillate around the axis 49. In the hooks 51 and 52 is fixed a bar 53 on which are soldered the filament strands; each bar, such as 53, supports two filaments such as 3' and 3''. A ring 54 passing in the hooks 14 maintains the spacing and the position of the filament strands. This ring is kept inside the hooks 14 by small hooks 54' soldered to the end of the hooks 14.

The operation of the apparatus shown in Figs. 7, 8 and 9 is as follows: The pivot assembly 47 and 48 enables the member 48 to take up such a position that the effort of the spring 19 is equally distributed on the axle 49. The rod 15, in turn, equally distributes between the strands 3 of the filament the effort exercised on the axle 49. It may be noted that the extremity of the member 45 is provided with a tapped opening and a slot 55 permitting it to be fixed on a tool for maintaining the filament in position when the filament is not yet introduced in the tube and the rod 16 and the mechanisms 14 and 15 have not contributed to maintain the filament in its definite position.

In order to insure the cooling of the anode 1, a special arrangement of cooling fluid jacket is provided and illustrated in Fig. 1. As has been seen above, the anode 1 may be constructed by means of a special copper tube of suitable size whose extremities are prepared so as to enable the glass portions to be sealed thereto. At the extremities of the anode there are soldered two rings, for example, two copper rings 22 and 23; the shape of these rings is clearly shown in Fig. 1. It will be noted that these rings 22 and 23 may be flared for a suitable distance so that these rings may be soldered at 24 to the tube forming the anode 1, and at 25 to the outer container 26 of the cooling fluid jacket. This container 26 may be suitably constructed by means of a tube concentric with the tubular anode 1. The shape of the outer container of the circulating cooling fluid jacket is clearly shown in Figs. 1 and 3. Although Fig. 3 shows an embodiment of the outer container of the cooling fluid jacket in the form of a tube of suitable size, it is obvious that this container may be constructed, for example, of two semi-cylinders suitably connected. When the container 26 is set in place according to Fig. 1, it will be noted that between the outer surface of the tubular anode 1 and the member 26 there is an empty space permitting circulation of the cooling fluid for the anode 1 which is brought to a high temperature by electronic bombardment. In order that the cooling fluid may circulate around the anode 1, in the form of a thin film actuated at high speed, annular members 27 and 28 are provided and arranged as shown in Figs. 1 and 3. Figs. 1 and 3 clearly show the shape and arrangement of these members with respect to the anode 1. The members 27 and 28 are arranged so that a fairly small empty space exists between the interior of these members and the outside of the anode. As this space determines the thickness of the layer of cooling fluid, the members 27 and 28 may be kept at a suitable distance from the anode 1 by means of spacers 29, riveted or soldered to the members 27 and 28 as clearly shown in Fig. 3. The members 29 may be formed by means of small angle-irons covering a more or less great length of the members 27 and 28. The members 27 and 28 are shorter than the anode as may be seen in Fig. 1, which enables fairly large channels 30 and 31 to be left free. The jacket for circulating the cooling fluid is, as has been shown above, formed

by the outer surface of the anode surrounded by a tube in one piece, which enables the outer part of the water jacket to be set in place after the mounting of the elements of the vacuum tube. The tightness of the jacket is obtained simply by means of two annular joints between members 26 and 24 and 26 and 23. The circulation of the cooling fluid is made in the following manner: The cooling fluid, for example, water, arrives under pressure through the tube 32 and is displaced according to the arrows shown in Fig. 1. The cooling fluid in passing in the relatively narrow annular space between the anode 1 and the guide members 27 and 28 takes on a high speed and rapidly disperses the heat produced by electronic bombardment. It is consequently possible to increase the power which may be dissipated in an anode of given dimensions. The space beyond the guide members 27 and 28 is filled with cooling fluid, but in view of the shape of the members 22 and 23, shown on the figure, no fluid circulation is produced in this space. It will be noted that the cooling fluid is introduced into the jacket 26 approximately in the middle while the outlet of the fluid is at both ends of the jacket so as to reduce the loading loss and consequently the pressure necessary to obtain the very active circulation of cooling fluid. It will thus be seen that in accordance with the foregoing, the arrangement described comprises a jacket for the cooling fluid particularly adapted for a double-ended tube, and adapted to be easily set in place after the mounting of the other elements of the tube. The jacket surrounds the tubular anode so as to leave a free space for the circulation of the cooling fluid, the fluid being conveyed to the jacket by means of a tube placed approximately in the middle of the jacket, the fluid being removed by means of at least two outlets placed approximately at opposite ends of the jacket and means being provided to insure the circulation of the cooling fluid in the form of a fine layer of very rapid circulation, so as to insure a maximum transfer of heat between the anode 1 and the cooling fluid.

Fig. 3 shows a section of the tube along line C—D. In Fig. 3 the outer container of the cooling fluid jacket is shown at 26 and the member 27 is designated by the same reference in Fig. 3 as in Fig. 1. It will be noted that the member 27 is formed by means of two semi-cylinders 27 and 27' fixed in position by suitable means, such as clamps 271, as is clearly shown in Fig. 3. The four rods supporting the grid are shown at 12 and the six filaments forming the cathode are shown at 3.

Fig. 4 is a section of Fig. 1 along line E—F. This figure clearly shows a screen 56 employed to reflect the heat radiated from the cathode 3 from the tubular conductors 4 and 5 and from the glass portion 21. This screen consists of the molybdenum disc fixed on three of the rods 13 supporting the filaments. The openings provided in the circular screen 56 for the passage of the three rods 13 are shown in the figure at 13', 13'' and 13''''. The screen 56 is fixed in position on these rods by suitable means, such for example, as by means of helical springs 57 fixed on the rods 13. In order to give more rigidity to the screen 56, a molybdenum ring is fixed by means of claws 58, 58' and 58'', on the periphery of the screen. It will be seen that the screen 56 is brought to the potential of the three rods 13', 13'' and 13''' supporting the filaments. Since there is a difference of potential between the two opposite extremities

of the filaments, it is necessary for the three other rods supporting the other extremities of the filaments to pass through the screen without making contact therewith because in the latter case the filaments would be short-circuited. For this purpose the screen 56 is provided with openings 131, 13'1 and 13''1 whose diameters are greater than the diameters of the supporting rods of the filaments.

Figs. 5 and 6 are sections of the tube of Fig. 1 along lines G—H and I—J, respectively, serving to explain the fixing of the filament support rods on the tubular conductors 4 and 5, which act as supports and convey current to the filaments. In Fig. 6 the conductors serving as filament supports are shown at 4 and 5. As has been seen in the description of Fig. 4, the six conductors forming the filaments are regularly arranged at each of the peaks of a hexagon and fixed to six metallic rods such as 13 and 13'; three of these rods are connected to the tubular conductor 4, for example, and the three others are connected to the other tubular conductor 5. Fig. 6 shows that three filament rods are supported by the tubular conductor 4 by means of block members 4', 4'', 4''' and 4'''' screwed on the conductor 4. The rods 13 are soldered to the arc in the members 4', 4'', 4'''', the corresponding rods are then placed at 120 degrees from each other. The three other filament rods are supported by means of a triangular member 59, Fig. 5, and are also 120 degrees from each other but the member 59 is arranged with respect to the members 4', 4'' and 4''' so that each filament supporting rod forms an angle of 60 degrees with the following rod or with that immediately preceding it. The member 59 is fixed by means of a screw 60, Fig. 1, on the tubular conductor 5. It will thus be seen that the whole forms an extremely rigid unit which may be set in position with great precision.

In order to protect the glass sheath and particularly at the points where the portions 2 and 2' are sealed to the anode, metallic electrostatic screens 61 and 62 may be provided as shown in Fig. 1. The free ends of these screens are turned back so as to form a flange permitting of the increase of rigidity of the screen and the decrease of the intensity of the electric field on the edge of the screen and consequently of the possibility of discharge. Screens 61' and 62' are also fixed to the ends of the grid, to limit the electron discharge to the cooled portion of the anode.

The fabrication of a tube such as that in Fig. 1 may be carried out in the following manner: The concentric tubular conductors 4 and 5 are assembled with the members 4', 4'', 4''' and 59 and the corresponding filament supporting rods; a rod is then introduced into the tube and fixed in position in the conductor 5. At the end of this rod which forms a mounting tool is fixed a slot 55 of the swivel member 15, serving to support one of the ends of the filament. The filament is then fixed on the unit thus established. The other elements of the tube having been assembled in advance, it is sufficient to introduce the whole filament and concentric tubular conductors 4 and 5 into the tube, then screw the rod 16 into the upper end of the member 15 and, after sealing the tube, to withdraw the rod, serving as a tool fixed in the slot 55 of the member 15 so that the mounting of the filament may be realized. A sufficient tension will be applied to the filament by manipulating the nut 20 associated with the rod 16.

- What is claimed is:
1. An electron discharge device comprising an anode, a multi-strand cathode associated with said anode, means rigidly fixing and spacing the strands of said cathode at one end, supporting means coupled to the strands of said cathode at the other end, and means including a rigid universally movable member supporting said second means. 80
  - 10 2. An electron discharge device comprising an anode, rigidly supported bilateral members, one of said members having a pivot extending therefrom, an intermediate member disposed between said bilateral members and rockably supported on said pivot, and a multi-section filament supported by said intermediate member. 85
  - 20 3. An electron discharge device comprising an anode, rigidly supported bilateral members, an intermediate member disposed between said bilateral members, means rockably mounting said intermediate member on one of said bilateral members, radial arms extending from said intermediate member, and a plurality of filament sections carried by said arms. 90
  - 30 4. An electron discharge device comprising an anode, rigidly supported bilateral members, an intermediate member yieldingly supported between said bilateral members, radial arms extending from said intermediate member, swinging bars carried by said arms, and uniform lengths of filament joined to the opposite ends of said bars. 95
  - 35 5. An electron discharge device comprising an anode, rigidly supported bilateral members positioned in the axis of said anode, an intermediate member yieldingly supported between said bilateral members, swinging bars carried by said intermediate member and extending beyond the edge of said bilateral members, hooks extending from said bars, and a filament section supported by 100 each hook. 105
  - 40 6. An electron discharge device comprising an anode, rigidly supported bilateral members positioned in the axis of said anode, an intermediate member yieldingly supported between said bilateral members, swinging bars extending from said intermediate member, hooks extending from the ends of said bars, parallel filament sections supported by said hooks, and a spacing member associated with said hooks. 110
  - 45 7. An electron discharge device comprising an anode, rigidly supported bilateral members positioned in the axis of said anode, an intermediate member disposed between said bilateral members, means supporting said intermediate member 115 from one of said bilateral members allowing universal movement of said intermediate member, swinging bars carried by said intermediate member, hooks extending from said bars, parallel filament sections supported by said hooks, and a ring 120 affixed to said hooks to insure uniform spacing between said filament sections. 125
  - 50 8. A double-ended electron discharge power tube comprising an external anode, glass portions sealed thereto at opposite ends, a single tubular conductor extending from one of said glass portions, concentric tubular conductors extending from the opposite glass portion, a helical grid within said anode and supported from said single tubular conductor, and a multi-strand filament 130 within said grid and anode supported from said concentric conductors at one end, and means supporting the other end of said filament by said single tubular conductor. 135
  - 55 9. A double-ended electron discharge power tube comprising an external anode, glass portions 140
  - 60
  - 65
  - 70
  - 75
- sealed thereto at opposite ends, a single tubular member extending from one of said glass portions, concentric tubular conductors extending from said other glass portion, a plurality of straight filament sections attached to each of said concentric conductors, and a yielding support carried by said tubular member and connected to said filament sections. 80
10. A double-ended electron discharge power tube comprising the combination of an external anode, glass portions sealed thereto at opposite ends, a single tubular member extending from one of said glass portions, concentric tubular conductors extending from said other glass portions, a plurality of straight filament sections attached to each of said concentric conductors, a guide member in said single tubular member, a rigid rod extending through said guide member, a supporting member attached to said rod and to said filament sections, and resilient supporting means for said rod in contact with said guide member. 85
11. A double-ended electron discharge power tube comprising an external anode, glass end portions sealed thereto at opposite ends, inner and outer concentric tubular conductors extending from one of said glass portions, a plurality of segmental blocks attached to one end of said outer conductor, a triangular block attached to one end of said inner conductor, a plurality of filament sections attached to said blocks, supporting means for said sections at the opposite ends thereof, and means coupling one section attached to said triangular block to a section attached to a segmental block. 90
12. An electron discharge device of the higher power type comprising an envelope formed of a metal portion and a glass portion, the metal portion serving as the anode of the device, inner and outer concentric tubular conductors extending from said glass portion, a plurality of straight filamentary sections supported in said metal portion, said sections being arranged in a circular boundary about an axis of said metal portion, alternate sections of said filament being connected to said inner and outer concentric conductors, and a heat shield interposed between said filament sections and said tubular conductors, said heat shield being supported by said filament sections extending from said inner conductor and having apertures allowing the free passage of said filament sections extending from said outer conductor. 100
13. A double-ended electron discharge power tube comprising an external anode, glass portions sealed thereto at opposite ends, a single tubular conductor extending from one of said glass portions, concentric tubular conductors extending from the opposite end portion, a plurality of guide members within said single tubular conductor, a sheath within said tubular conductor for positioning said guide members therein, a rigid rod extending through said guide members, a plurality of filament sections extending between said concentric tubular conductors and said rod, 110 said single tubular conductor having a boss limiting the movement of said sheath in one direction, and adjustable resilient means engaging said support rod for limiting the movement of said sheath and guide members in the opposite direction. 115
14. An electron discharge tube comprising an external anode, a glass portion sealed thereto, a filament within said anode supported from said glass portion, a cooling jacket surrounding said 120
